UNITED STATES PATENT OFFICE.

HERMAN L. GREVE, OF BROOKLYN, NEW YORK.

DESIGN FOR A CARTON.

Application filed September 7, 1926. Serial No. 18,993. Term of patent 14 years.

To all whom it may concern:

Be it known that I, HERMAN L. GREVE, a citizen of the United States, residing at #357 Macon St., borough of Brooklyn, city of New York, State of New York, have invented a new, original, and ornamental Design for Cartons, of which the following is a specification, reference being had to the accompanying drawings, forming part thereof.

I claim:

The ornamental design for a carton, as shown.

HERMAN L. GREVE.
